(74) Attorney, Agent, or Firm—Duane Morris, LLP

(57) **CLAIM**

The ornamental design for a shower curtain rod fitting, as shown and described.

DESCRIPTION

FIG. 1 is a perspective view of a shower curtain rod fitting showing my new design in its environment, namely, mounted to a pair of rods. The rods and opposing fitting are shown in broken lines for illustrative purposes only, and form no part of the claimed design;

FIG. 2 is a front elevation view of the fitting of FIG. 1;

FIG. 3 is a elevation view of the fitting of FIG. 1;

FIG. 4 is an elevation view from the right side of the fitting of FIG. 1;

FIG. 5 is an elevation view from the left side of the fitting of FIG. 1.
